CLAIM

I claim the ornamental design for a combined stand and cover for displaying sugar wafers, substantially as shown and described.

DESCRIPTION

FIG. 1 is a perspective view of a combined stand and cover for displaying sugar wafers showing my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.
